11 Claims. (Cl. 315—27)

1

This invention relates to television, and more particularly to improved cathode ray beam deflection signal generators.

Image reproduction by electronic viewing devices has been generally accepted as the most desirable and has met with outstanding success. Consequently, the cathode ray viewing tube is almost universally used today in television receivers.

The reproduction of images is accomplished by analyzing the scene into its picture elements by a predetermined sequence of scanning and transmitting energy representative of each picture element for reconstruction at the receiving point by the same scanning sequence.

In order to produce scanning, the beam must be moved across the screen independently in two directions and at right angles to each other. It is preferable to deflect the beam through an angle at a position close to the end of the gun. This deflection of the electron beam can be accomplished by either an electrostatic field produced by a pair of deflecting plates or a magnetic field set up at right angles to the direction of deflection and produced by an inductance coil. Each of these methods has been successful in practical application as a means for producing electron beam deflection.

Magnetic deflection for both vertical and horizontal displacement of the electron beam has become almost universal in application for employment on large cathode ray tubes.

Magnetic deflection is accomplished by establishing an electromagnetic field close to the end of the gun. The deflection is at right angles to the direction of the magnetic field of lines, and the field is usually produced by a pair of iron or air-cored electromagnets placed outside of the gun neck portion of the tube.

If the tube is provided with suitable shaped coils and cores, a perfect scanning pattern can be obtained only if they are supplied with current or voltage having a very specific time variation. The wave form of current through the inductance coils producing the vertical deflection of the electron beam must be sawtoothed and have a recurring frequency equal to the field frequency of the pattern. The current through the horizontal coils must also be sawtoothed, but its repetition frequency is much higher and corresponds to the desired line frequency.

The current in each case builds up substantially linearly with time for most of the cycle, and then returns rapidly to its initial value.

The deflection signal generator which supplies

2

the power to these deflecting elements generally consists of an oscillator, a sawtooth generator and a deflection amplifier. The oscillator is normally set off by a series of synchronizing pulses which serve to coordinate the timing of the scanning rasters at the transmitter and receiver.

Although the early forms of cathode ray deflection systems generally employed a simple gaseous discharge sawtooth wave generator, the exact requirements of television in its improved forms have placed stringent requirements for both speed and velocity on the deflection system to make it necessary to employ thermionic devices together with wave shaping circuits to furnish the necessary deflection energy.

There are three distinct portions of the line deflecting cycle, which may be outlined as (a) the major portion of the "go" sweep, during which time the output tube of the deflection generator supplies current to the deflection yoke, (b) the interval of "free" oscillation (retrace time) during which time the output tube plate current is cut off and the wave form is determined by the circuit constants of inductance, capacity, and resistance, and (c) the portion following the return sweep, during which the free oscillation must be damped and energy which has been stored in the yoke inductance is permitted to be discharged, preferably in a controlled manner.

The driver tube portion of the "go" cycle was of major interest in early designs of cathode ray tube systems. Particular emphasis was placed upon obtaining a yoke current, which was a linear function of time.

However, the cathode ray tubes in general use today for television systems and the like are of the flat-faced wide-angle kinescope types. It therefore becomes necessary to modify the yoke current to allow for the deflection geometry of such tubes. For a properly designed deflection yoke, the deflection angle is approximately a linear function of the yoke current. Therefore, for small deflection angles, particularly when the tube face radius approximates the deflection radius, the spot displacement is a linear function of the yoke current. However, when the tube face radius and the deflection radius differ radically, and particularly for wide deflection angles, the yoke current must be distinctly non-linear in order to obtain a linear spot displacement.

According to this invention, there is provided an improved deflection system wherein the deflection current is conveniently adjustable to provide the necessary non-linearity in change of cur-

rent to obtain the necessary linear scanning spot displacement.

The interval of "free oscillation" or retrace time during which the output tube plate current is cut off has heretofore been taken care of by utilizing a high degree of damping. Part of this damping was in some cases inadvertently slighted by the output tube which, although supposedly at cut-off insofar as grid signal was concerned, frequently was not cut off. Additional damping was introduced by losses in the coupling transformer and yoke, and in some cases sufficient additional resistance was added in shunt with the yoke in order to make the circuit aperiodic. Obviously, this method of damping had the disadvantage of causing losses during the "go" sweep, as well as during the return sweep, and hence the deflection efficiency of the system was low.

It has been proposed to improve the circuit characteristics in efficiency by using a series resistance-capacity combination for damping. This tended to decouple the damping resistor during the slower "go" time and yet provide close coupling to the damping load during the rapid return time. Generally satisfactory results were obtained for the relatively slow 441-line standards, however, with the introduction of the 525-line standard, the return time of an aperiodic system is rather long, so that new damping procedures were proposed.

Circuits employing triode and diode damping in the secondary of the deflection transformer have met with considerable success, however, a perfect coupling in a deflection transformer is difficult to obtain and would be costly to produce, due primarily to the high voltage insulation which is required. A certain amount of decoupling with the damping element across the secondary of the deflection transformer results in a carry-over voltage in the primary of the deflection transformer which causes the output tube to produce spurious oscillation, such as the well-known Barkhausen oscillations.

The cause of the Barkhausen effects can be attributed to the negative excursion of the anode potential of the output tube due to the transients obtained upon a rapid change in current through an inductive element such as the deflection transformer.

According to this invention, there is provided a circuit arrangement whereby the output tube is rendered inoperative during the negative excursion of its anode potential, thus preventing the spurious signals resulting from Barkhausen oscillations.

A primary object of this invention is to provide for an improved cathode ray beam deflection system.

Another object of this invention is to provide an improved television system.

Other and incidental objects of the invention will be apparent to those skilled in the art from a reading of the following specification and an inspection of the accompanying drawing in which:

Figure 1 illustrates schematically one form of this invention;

Figure 2 illustrates face-plate curvature of typical commercial cathode ray tubes;

Figure 3 shows graphically wave shape of the anode voltage of a typical output tube in a deflection system; and

Figure 4 illustrates graphically yoke current variation.

Turning now in more detail to Figure 1, there is illustrated one form of this invention wherein an output tube 1, such as, for example, the type 6BG6-G or the type 807, which contains a control electrode 2 adapted to receive a sawtooth wave as illustrated through the associated input circuit comprising the capacitive element 3 and a resistance element 5.

The generation of sawtooth wave forms in accordance with a predetermined synchronizing pulse is well known in the art and needs no detailed explanation here, except perhaps to refer to Chapter IV, beginning on page 118 of "Principles of Television Engineering" by Donald G. Fink, wherein the formation, deflection and synchronization of scanning beams is very well described in detail. Deflecting circuits are also well known in the patented art, such as, for example, the U. S. patent to W. A. Tolson et al. No. 2,101,520, dated December 7, 1937; and the U. S. patents to W. A. Tolson Nos. 2,108,152, dated February 15, 1938, and 2,280,733, dated April 21, 1942.

The horizontal or line deflecting yoke 7 of the cathode ray tube 9 is coupled to the output of tube 1 by transformer 11.

Image producing tubes of the kinescope type are also well known to the art, and a description may be found in an article by Dr. V. K. Zworykin entitled "Description of an experimental television system and kinescope," in the "Proceedings of the Institute of Radio Engineers," vol. 21, No. 12, for December 1933, or the information beginning on page 329 of the book "Television" by V. K. Zworykin and G. A. Morton, published in 1940 by John Wiley & Sons, Inc.

The kinescope may be included in the image projection system of the type shown in the U. S. patent to Daniel A. Landis, No. 2,273,801, dated February 17, 1942.

Although the description of this invention will be limited to image reproducing systems, the invention is, of course, applicable to any scanning device.

45 A typical deflection yoke is shown and described in detail in the U. S. patent to W. A. Tolson, No. 2,167,379, dated July 25, 1939.

It is well established that the magnetic field set up by the deflection yoke 7 is proportional to the product of the number of turns in the coil and the current flowing in them. Therefore, the amount of current required in the coils depends directly on the number of turns in the coils. It is important, particularly in circuits involving rapid deflection, that not too large a value of inductance be employed. It is therefore necessary to supply a relatively large value of current to the deflecting yoke 7. It follows that high currents will necessitate the consideration in the deflection system of extremely high peaked voltages which are generated in the inductance coils when the current through them changes suddenly.

The scanning yoke has associated with it a distributed capacitance which, acting with the inductance of the yoke, forms a resonant circuit. The sudden shock caused by the sawtooth wave form of the driving current tends to set the resonant circuit into oscillation. The undesired oscillations in the voltage wave form produce corresponding irregularities in the current wave form which are reproduced in the scanning motion.

It has been the general practice to employ a rectifier, such as the diode damping tube 13 or 75 any other form of unit such as one of the semi-

conductor crystals, to reduce the undesired oscillation. The diode 13 is connected across the circuit involving the secondary of the transformer 11 and the deflecting yoke 7 and is connected in series with a capacity 15 and resistance element 17. Resistance element 17 may be made variable as shown.

The operation of the damping tube 13 is well known in the art, and additional information thereon may be obtained by reference to a co-pending U. S. application of Otto H. Schade, Serial No. 593,161, filed May 11, 1945, wherein there is shown and described a damping tube, together with power feed-back for utilization of the rectified currents in conjunction with the output tube anode potential.

If the transformer 11 were so constructed that it would have perfect coupling, the effect of the diode damper tube 13 would be projected back to the primary of transformer 11 in such a manner that there would be no negative excursion of voltage on the plate of tube 1 due to the extremely high peak voltages employed. However, in the practical consideration and design of transformer 11, it is necessary to arrive at a compromise on coupling such that the effect of the inductance on the transformer is to cause a negative excursion of voltage on the tube 1.

The negative excursion referred to may best be understood by reference to Figure 3, which for the most part is believed to be self-explanatory, except perhaps to state that the wave shape shows the plate voltage of a typical power output tube such as a 6BG6—G, which oscillates to —1900 volts at the beginning of the forward trace for "go" sweep. This negative excursion will cause the output tube to produce Barkhausen oscillations, which may readily affect the radio frequency section of the television receiver at high frequencies. The oscillations will be carried through the circuit to modulate the kinescope grid and will appear as vertical bars at the left edge of the image. The effect of the Barkhausen oscillations will not be observed when the scanning circuit alone is tested. The effect is generally found only when the complete receiver is in operation and tuned to the higher frequency channels and when high intermediate frequency gain is employed.

Returning now to Figure 1, there is included a tube 19 having its cathode 21 connected to an auxiliary control electrode 23 of tube 1. The anode of tube 19 is connected to a source of positive potential. The control electrode 24 of tube 19 is connected to the anode of diode 13 through a wave forming circuit comprising, for example, a pair of potentiometers 25 and 27. Potentiometer 25 is adapted to supply a variable current to a parabolic wave forming network including resistors 29 and condensers 31. Potentiometer 27 is adapted to supply a sawtooth wave forming circuit including resistors 33 and condenser 35. The output signal from the parabolic wave forming circuit and the sawtooth wave forming circuit is fed to the control electrode 24 through capacity 37. A D.-C. blocking condenser 38 is included in the circuit between diode 13 and potentiometers 25 and 27.

The function of tube 19 is to drop the potential of auxiliary control electrode 23 of tube 1 during the negative excursion of plate voltage of tube 1. A suitable delay of the negative surge on the secondary of element 11 through adjustment of 33 and 20, and amplitude adjustment with 25 and 27 during this interval will cause control elec-

trode 24 to go negative. This in effect opens the circuit at tube 19 so that the potential of control electrode 23 of tube 1 will go immediately towards or below its associated cathode potential. By dropping the potential of control electrode 23 to a sufficiently low value, there will be prevented in tube 1 any tendency toward Barkhausen oscillations.

It may also be added that the useless negative excursion referred to unnecessarily abuses the output tube 1 insofar as interelectrode insulation stresses are concerned and furthermore, the power obtainable from the output tube 1 is normally limited by the screen dissipation. The employment of this invention, therefore, reduces the abuses of the output tube, but permits a greater efficiency of operation. It is also possible to employ lower plate voltages in the output tube by obtaining greater efficiency in its operation.

In addition to preventing Barkhausen oscillations, the tube 19 may be utilized to control the wave shape of the deflection voltages through the parabola forming and sawtooth forming networks including elements 20, 31, 33 and 35. By properly selecting the values of these elements, many desired wave shapes may be obtained. Other wave shapes may be obtained by returning 25 and 27 to an extension of the secondary 30 of 11 below the tap herein connected to +B, instead of grounding 25 and 27. This extension would generate positive voltage surges during retrace and permit the generation of opposite polarities of parabola and sawtooth waves.

The adjustable wave shapes of the deflection current may be used to advantage, for example, in providing the non-linear yoke current required to obtain a linear spot displacement in the modern kinescope tubes having a substantially flat tube face. This will be more readily understood after a brief reference to Figures 2 and 4.

In Figure 2, there is shown a graphic determination of required yoke current wave shape on the basis of face-plate curvature. The curvature as illustrated in Figure 2 is typical of commercially produced kinescopes and is taken by way of example from the 7DP4 and 10BP4 types.

In Figure 4 there is shown a yoke current curve. The dashed line is straight and would be desirable 50 for a tube having a spherical screen surface whose radius is equal to the beam throw from the apparent center of deflection. When, however, the surface is flattened out, as illustrated in Figure 2, there is less deflection rate required at the beginning and end of the course, hence it is necessary to provide a yoke current as shown in the solid line of the curve shown in Figure 4. Such a yoke current curve, as well as other forms, may be provided by the use of this invention.

Linearity measurements usually refer to measurements made at the face of the kinescope. The unit length commonly used as the basis of production linearity testing is 10% of the useful scan. If the number of bars per unit length is within $\pm 10\%$ of the number scanned at the center of the screen, then the linearity is said to be 65 10%. Strictly speaking, the spot velocity is what is actually being measured if the intervals of measurement are sufficiently small. Methods 70 for measurement of the angular velocity of the deflection beam may be coordinated with the velocity data of Figure 2 to provide an approximate method of measurement. In this event, the free-running speed of the blocking oscillator

should be adjusted to the nominal horizontal line frequency.

Having thus described the invention, what is claimed is:

1. In a beam deflection system, beam deflection means, a power tube having an output circuit and an auxiliary control electrode, a coupling circuit between said output circuit and said beam deflection means, a control voltage circuit connection between said beam deflection means and said auxiliary control electrode, said control voltage circuit connection including parabola wave forming network.

2. In a television deflection system, a beam deflection coil, a power tube having an output circuit and an auxiliary control electrode, a coupling circuit between said output circuit and said beam deflection coil, and means for reducing spurious oscillations in said beam deflection coil comprising a control voltage circuit connection between said beam deflection coil and said auxiliary control electrode, said control voltage circuit connection including a tube having a cathode connected to said auxiliary control electrode and a control electrode connected to said beam deflection coil through a wave form changing network.

3. In a television deflection system, beam deflection means, a power tube having an output circuit and an auxiliary control electrode, a coupling circuit between said output circuit and said beam deflection means, and a control voltage circuit connection containing a cathode follower type tube connected between said beam deflection means and said auxiliary control electrode to control the potential of said auxiliary control electrode during predetermined time intervals.

4. In a television deflection system, beam deflection means, a power tube having an output circuit and an auxiliary control electrode, a coupling circuit between said output circuit and said beam deflection means, and a cathode follower connected amplifier tube connected between said beam deflection means and said auxiliary control electrode to control the potential of said auxiliary control electrode during voltage surges across said beam deflection means.

5. In a television deflection system, beam deflection means, a power tube having an output circuit and an auxiliary control electrode, a coupling circuit between said output circuit and said beam deflection means, and a wave shaping circuit connection between said beam deflection means and said auxiliary control electrode, said wave shaping circuit comprising a cathode coupled amplifier tube connected serially with a parallel connected sawtooth wave and parabola wave forming electrical networks.

6. In a television deflection system, beam deflection means, a power tube having an input circuit adapted to receive a sawtooth wave, an output circuit and a current control electrode, a coupling circuit between said output circuit and said beam deflection means, and a parabola wave forming network connected between said beam deflection means and said current control electrode.

7. In a television deflection system, beam deflection means, a power tube having an input circuit adapted to receive a sawtooth wave, an output circuit and a current control electrode, a cou-

pling circuit between said output circuit and said beam deflection means, and a sawtooth wave and parabola wave forming network connected between said beam deflection means and said current control electrode.

8. In a television deflection system, beam deflection means, a power tube having an input circuit adapted to receive a sawtooth wave, an output circuit and a current control electrode, a coupling circuit between said output circuit and said beam deflection means, an auxiliary control tube having a cathode, a control electrode and an anode, said cathode connected to said current control electrode, said anode connected to a source of positive potential, and a control voltage connection between said beam deflection means and said control electrode.

9. In a television deflection system, beam deflection means, a power tube having an input circuit adapted to receive a sawtooth wave, an output circuit and a current control electrode, a coupling circuit between said output circuit and said beam deflection means, an auxiliary control tube having a cathode, a control electrode and an anode, said cathode connected to said current control electrode, said anode connected to a source of positive potential, and a circuit connection between said beam deflection means and said control electrode including serially connected resistances and parallel connected capacity.

10. In a television deflection system, beam deflection means, a power tube having an input circuit adapted to receive a sawtooth wave, an output circuit and a current control electrode, a coupling circuit between said output circuit and said beam deflection means, an auxiliary control tube having a cathode, a control electrode and an anode, said cathode connected to said current control electrode, said anode connected to a source of positive potential, and a circuit connection between said beam deflection means and said control electrode having serially connected resistance and parallel connected capacity.

11. In a television deflection system, beam deflection means, a power tube having an input circuit adapted to receive a sawtooth wave, an output circuit and a current control electrode, a coupling circuit between said output circuit and said beam deflection means, an auxiliary control tube having a cathode, a control electrode and an anode, said cathode connected to said current control electrode, said anode connected to a source of positive potential, and a sawtooth wave and parabola wave forming networks connected between said beam deflection means and said control electrode.
